Primary Examiner — Catherine A Tuttle

(57) **CLAIM**

The ornamental design for the boxing speed ball, as shown and described.

DESCRIPTION

FIG. 1 is a front view of the boxing speed ball showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof; and,

FIG. 8 is bottom perspective view thereof.

The broken lines in FIGS. 6 and 7 depict portions of the boxing speed ball that form no part of the claimed design.

1 Claim, 8 Drawing Sheets
